DESIGN FOR A COMBINED POWDER COMPACT, CIGARETTE CASE, LIGHTER, WATCH AND HOLDER THEREFOR, AND LIPSTICK CASE

Paul E. Flato, New York, N. Y.

Application October 12, 1940, Serial No. 95,792

Term of patent 3½ years

To all whom it may concern:

Be it known that I, Paul E. Flato, a citizen of the United States of America, residing in New York city, county of New York, and State of New York, have invented a new, original, and ornamental Design for a Combined Powder Compact, Cigarette Case, Lighter, Watch and Holder Therefor, and Lipstick Case, of which the following is a specification, reference being had to the accompanying drawings, forming part thereof, wherein,

Figure 1 is a front elevational view of a combined powder compact, cigarette case, lighter, watch and holder therefor, and lipstick case, showing my new design in closed position.

Figure 2 is a side elevational view thereof;

Figure 3 is a top plan view thereof;

Figure 4 is a fragmentary front view thereof with the watch and holder portion in raised position;

Figure 5 is a side elevational view of Figure 4;

Figure 6 is a fragmentary front elevational view with the lighter insert in raised position;

Figure 6a is a front elevational view of the lighter insert;

Figure 7 is a bottom plan view of the combined article with the lipstick insert removed therefrom.

Figure 7a is a front elevational view of the lipstick insert.

Figure 8 is an open front view of the combined article showing the powder compact compartment; and

Figure 9 is a similar view of the other side showing the cigarette compartment.

The dominant features of my design reside in the portions shown in full lines.

I claim:

The ornamental design for a combined powder compact, cigarette case, lighter, watch and holder therefor, and lipstick case, substantially as shown and described.

PAUL E. FLATO.
